CIRCUMCISION BOARD

Maurice Black, Saginaw, Mich.

Application September 28, 1953, Serial No. 382,539

8 Claims. (Cl. 311—5)

This invention relates to circumcision boards for use in hospitals and clinics, and more particularly to a device for holding a baby in prone position and rendering his arms and legs relatively immobile.

As is well known, one or more nurses are presently required to hold the legs and arms of a squirming baby while a doctor performs an operation such as a circumcision on the baby.

One of the prime objects of the instant invention is to provide an operating board on which the baby can be placed and strapped, to hold the baby in proper position and immobile, eliminating the necessity of having one or more nurses in attendance to hold the baby's arms and legs.

A further object of the invention is to design an operating board which is provided with straps for holding the baby in position, the straps being individually longitudinally adjustable relative to the length of the board and baby so that babies of varying size and limb length can be accommodated thereon.

Another object of the invention is to design an operating board which is tapered toward the foot end thereof so that the position of the baby on the board can be adjusted to permit the straps to effectively hold the baby while applying a minimum amount of pressure to accomplish the purpose. The more nearly the width of the portions of the baby's body which are to be engaged by the straps conform to the width of the board, the less pressure will be exerted by the straps to retain the baby in position.

A further object of the invention is to design an operating board of the type described, which is capable of effectively holding the child in prone position without uncomfortably binding him and which decreases the possibility of inadvertent injury to the child during the operation due to his squirming.

Another object of the invention is to provide an operating board of the type described which is of strong and durable construction and is light in weight and readily portable.

A further object of the invention is to design an operating board which may be supported on level surfaces such as the tops of operating tables at any angle which is convenient.

Another object of the invention is to provide an operating board of simple and practical design on which a child can be very rapidly secured in position.

A further object of the invention is to design an operating board of the type described which can be readily sterilized and thence conveniently stored until it is desired to employ the device over again.

A still further object of the invention is to design an operating table composed of few component parts which cannot slip off the device and become lost, and which can be simply and economically manufactured and assembled.

With the above and other objects in view, the present

2

invention consists in the combination and arrangement of parts, hereinafter more fully described, illustrated in the accompanying drawings, and more particularly pointed out in the appended claims, it being understood that changes may be made in the form, size, proportion, and minor details of construction, without departing from the spirit, or sacrificing any of the advantages of the invention.

In the drawings:

10 Fig. 1 is a top plan view of my operating board showing a child secured in position thereon.

Fig. 2 is a transverse sectional view taken on the line 2—2 of Fig. 5.

Fig. 3 is a head end elevational view of the device.

Fig. 4 is an opposite end elevational view thereof.

Fig. 5 is a fragmentary, side elevational view of the device, the broken lines indicating adjusted positions of the strap brackets.

Referring now more particularly to the accompanying drawings in which I have shown the preferred embodiment of my invention, a letter O generally indicates my operating board which comprises a raised support surface or table 10 including legs or sides which are formed by turning the side edge portions of the table 10 downwardly as at 11, and thence inwardly as at 12, the legs terminating in reversely turned portions 13 to form tracks which slidably accommodate the strap brackets 14. It will be apparent that the formation of the legs in the manner described, reinforces the portions 11, and that the operating board can, of course, be readily formed from a lightweight sheet metal such as aluminum which will not rust when subjected to repeated sterilizations.

The lower ends of the vertically disposed strap brackets 14 are turned inwardly as at 15, thence reversely as at 16, thence horizontally outwardly as at 17, and finally terminate in depending guide portions 18. Thus, it will be seen that the lower ends of the brackets 14 embrace the legs of the support surface in a manner which insures that they cannot become readily disengaged. Further, at both ends of the device, the track portions 13 are crimped as at 19 to close the spaces between the portions 11 and 13 of the legs which accommodate the guide portions 18 of the brackets to prevent the bracket from slipping off the ends of the device. The upper portions of the brackets project above the table 10 and are formed with openings 20 therein to accommodate the straps 21, the latter comprising conventional fabric straps which are provided with buckles 22 as usual.

It will be observed that the board is tapered from one end thereof to the other to conform generally to the shape of a child. In practice, the child is placed on the board which may be supported on a conventional operating table (not shown) in a position wherein the width of his chest and arms most nearly conform to the width of the board. In this position, the straps 21 need be less tight to retain the child than is necessary where the effective length of the straps relative to the width of the child's body is greater. In this regard, also, it is important to note that the straps are connected to the brackets above the table 10 so that their effective length is kept at a minimum. Generally a pad (not shown) will be placed on the table 10 underneath the child as might be expected. To provide convenient handholds for handling the device and to lend rigidity thereto, the end edge portion of the table 10 is turned downwardly at the head end of the device as at 23, and the end edge of the board is turned downwardly at the foot end of the device as at 24.

The fact that the weight of the child and table is supported on the strap brackets 14 precludes any possibility

of their shifting once they have been properly adjusted and the child is secured in position.

It will thus be apparent that I have perfected a very simple, inexpensive, and practical operating board which is ideally suited to hold a child in prone position so that a circumcision or the like may be performed with a minimum of attendant medical personnel. It is anticipated, however, that the device may be employed for other purposes such as bathing of a baby, and it is to be understood that I intend the instant disclosure to be illustrative rather than limiting. In this connection, it is further to be understood that various equivalent changes may be made in the design and shape of the various component elements of the device without departing from the spirit of the invention or the scope of the appended claims.

What I claim is:

1. In an operating board, an elongated support surface on which a child may be secured in prone position including side wall sections for said board on which said board may be supported, substantially longitudinally disposed track means formed in said side wall sections, opposed strap brackets slidable longitudinally on said track means and adjustable lengthwise on said support surface, and adjustable strap means spanning said brackets to secure a child in position on said board.

2. The combination defined in claim 1 in which said brackets are vertically disposed and project above the support surface, the straps being connected thereto adjacent the upper ends thereof.

3. The combination defined in claim 1 in which said track means are formed by turning the terminal edges of said legs inwardly and reversely, and the brackets embrace said legs so that the weight of the board and child is borne thereon, said brackets terminating in guide portions which are slidable in said track means.

4. The combination defined in claim 1 in which the end edge portions of said support surface are turned downwardly to provide handholds and reinforce said surface.

5. In an operating board, an elongated, tapered, raised support surface on which a child may be secured in prone position, including sides formed by turning the side edge portions of the support surface downwardly, the sides being thence turned inwardly and terminating in upwardly projecting track sections, vertically disposed pairs of brackets on the sides of said support surface longitudinally adjustable in said track sections, the lower ends of said brackets being turned inwardly and thence upwardly to embrace the sides of said support surface and terminating in depending guide portions disposed between said sides and track sections, and adjustable straps spanning said brackets to firmly secure the legs, torso, and arms of said child.

6. The combination defined in claim 5 in which the ends of said track sections are crimped to the sides of said support surface to prevent the brackets from slipping off the ends of said surface.

7. The combination defined in claim 6 in which the brackets extend above the support surface, and openings are provided in the upper ends thereof for connection of said straps.

8. In a circumcision board, an elongated support board tapering so that children of varying size may be placed thereon in a prone position with the width of their bodies corresponding substantially to the width of the board at a given location on the board, guide means on the sides of said support board, strap brackets associated with said guide means movable lengthwise on the sides of said board, and strap means spanning said board connected to said bracket for securing a child in position.
